(57) **CLAIM**

The ornamental design for a light fixture, as shown and described.

DESCRIPTION

FIG. 1 is an isometric view of a first embodiment of the light fixture of the present invention;

FIG. 2 is a front elevation view thereof;

FIG. 3 is a right side elevation view thereof, the left side elevation view being a mirror image thereof;

FIG. 4 is top plan view thereof;

FIG. 5 is a bottom plan view thereof;

FIG. 6 is a rear elevation view thereof;

FIG. 7 is a front elevation view of a second embodiment thereof, incorporating the same design shown in FIGS. 1-6 in a smaller fixture; and,

FIG. 8 is a front elevation view of a third embodiment thereof, incorporating the same design shown in FIGS. 1-6 in a slightly larger fixture.

The broken line shown is for illustrative purposes only and forms no part of the claimed invention.
